RALPH B. POLK, OF HAINES CITY, FLORIDA

APPARATUS FOR PACKING MATERIALS

Application filed May 26, 1928. Serial No. 280,824.

There are many articles, especially food products, which may advantageously be packed in carefully arranged order within the package but difficulty is experienced in producing an orderly arrangement of material in the package even where the package is of the wide mouth type such for instance as glass jars or tin cans.

The object of my present invention is to provide an improved process by which the desired orderly arrangement may be attained rapidly and efficiently and to provide mechanism for facilitating the practice of the process.

The accompanying drawings illustrate my invention.

Fig. 1 is a side elevation of my improved apparatus, with an associated package in partial vertical section, the parts being in the positions occupied at the time of discharge of the prearranged materials into the package.

Fig. 2, a fragmentary vertical section with the parts in initial loading position.

Fig. 3, a view similar to Fig. 2 with the parts in an intermediate loading position.

Fig. 4, a view similar to Figs. 2 and 3 with the parts in final loading position and the package in position just prior to reversal of the parts preliminary to loading of the package.

Fig. 5, a plan, in partial horizontal section, of the parts shown in Fig. 1 and,

Fig. 6, a plan, about full size, of the loading cylinder showing the arrangement of grape fruit or orange segments therein.

In the drawings 10 indicates a cylindrical casing or receptacle formed of a thin non-corroding material and having an external diameter a trifle less than the diameter of the mouth of the ultimate container which is to be filled and a length somewhat greater than the length of such ultimate container. In the drawings the ultimate container 11 is indicated as an ordinary tin can of the vacuum sealing type. Cylinder 10 is supported by a swinging plate 12 pivoted on a horizontal axis 13 at the upper end of a supporting bracket 14 having a pair of horizontally arranged laterally separated fingers 15, 15 upon

which plate 12 may rest when the parts are in the position shown in Fig. 4. Slidably mounted within the cylinder 10 is a piston or head 20 having a pair of diametrically opposed pins 21, 21 projected therefrom through slots 22 formed through the wall of cylinder 10. Piston 20 is provided with a stem 23 which projects through and is guided in plate 12 and provided at its lower end with a knob 24 by which it may be conveniently manipulated. A screw 25 of convenient length is threaded through plate 12 into the closed end of cylinder 10 so as to form an adjustable abutment for piston 20 and thus regulate its extreme position relative to the open end of cylinder 10.

In order to sustain the weight of piston 20, and material superposed thereon, at any desired vertical position of piston 20, I provide a spring finger 30 which frictionally engages stem 23.

Assuming that orange or grape fruit segments are to be packed in an attractive and orderly manner the operation will be as follows:

The operator will first swing plate 12 from the position shown in Fig. 1 to the position shown in Fig. 4 where it will rest upon the fingers 15 of bracket 14, and will move piston 20 to its upper position as shown in Fig. 2 where it presents an easily accessible platform upon which the segments of orange or grape fruit may be laid in an orderly manner as shown in Fig. 2, the operator being unhampered by any need to enter deeply into the cylinder 10. When this arrangement has been accomplished piston 20 will be moved downwardly a short distance where it will be held in place by the friction of spring 30. Segments 40 (Fig. 3) may then be laid upon the semi-spherical group 41 to form a substantially horizontal surface. Piston 20 may then be moved downwardly to a position shown in Fig. 3 whereupon a second semi-spherical group 42 of fruit segments may be readily placed, preferably at right angles to the segments of group 41. This operation will be repeated until piston 20 has been brought to its lowest position as determined by the stop screw 25 and the cylinder 10 is

properly filled. Thereupon the can 11 is inverted and slipped over cylinder 10, as shown in Fig. 4; its open end resting upon pins 21 of piston 20. Thereupon the operator swings the cylinder 10 to the position shown in Fig. 1 and, by pressing downwardly upon knob 24 positively forces the container and pack downwardly from the cylinder 10. It will be noted that by this arrangement the stripping of the can 11 from the cylinder 10 does not require the exertion of any pressure upon the arranged material so that that material is inducted into the can without distortion or disarrangement.

It has been found in practice that by the use of the described apparatus and a practice of the procedure outlined above an exceedingly attractive pack may be produced at a very much lower cost than has heretofore been possible and that the material is arranged in the can much more orderly and attractively than has heretofore been at all possible.

I claim as my invention:

1. A packaging device comprising a supporting bracket, a swinging plate pivotally mounted at one edge on said bracket on a horizontal axis, stops arranged to limit the swing of said plate from a horizontal receiving position to an inverted discharge position, a receptacle, approximating in cross-section the cross-section of the mouth of an ultimate container, mounted upon one face of said plate, a stem projected through said plate and having a length greater than the depth of the receptacle, a piston carried by one end of said stem within the receptacle, means yieldably supporting said stem and piston in various positions of adjustment.

2. A packaging device comprising a supporting bracket, a swinging plate pivotally mounted at one edge on said bracket on a horizontal axis, stops arranged to limit the swing of said plate from a horizontal receiving position to an inverted discharge position, a receptacle, approximating in cross-section the cross-section of the mouth of an ultimate container, mounted upon one face of said plate, a stem projected through said plate and having a length greater than the depth of the receptacle, a piston carried by one end of said stem within the receptacle, means yieldably supporting said stem and piston in various positions of adjustment, and means connected with the stem and lying outside the receptacle for engaging an ultimate container telescoped over the receptacle by which said container may be stripped from the receptacle by pressure exerted on the stem.

3. A packing device comprising a supporting bracket, a swinging plate pivotally mounted at one edge on said bracket on a horizontal axis, stops arranged to limit the swing of said plate from a horizontal receiving

position to an inverted discharge position, a receptacle, approximating in cross-section the cross-section of the mouth of an ultimate container, mounted upon one face of said plate, a stem projected through said plate and having a length greater than the depth of the receptacle, a piston carried by one end of said stem within the receptacle, means carried by the other end of the stem for limiting the play of the stem through the plate; friction means acting on the stem to hold it and the imposed load at various positions of adjustment.

4. A packaging device comprising a supporting bracket, a swinging plate pivotally mounted at one edge on said bracket on a horizontal axis, stops arranged to limit the swing of said plate from a horizontal receiving position to an inverted discharge position, a receptacle, approximating in cross-section the cross-section of the mouth of an ultimate container, mounted upon one face of said plate, a stem projected through said plate and having a length greater than the depth of the receptacle, a piston carried by one end of said stem within the receptacle, means carried by the other end of the stem for limiting the play of the stem through the plate; friction means acting on the stem to hold it and the imposed load at various positions of adjustment, and means connected with the stem for engaging an ultimate container sleeved over the receptacle.

In witness whereof, I have hereunto set my hand at Haines City, Florida, this 10th day of May, A. D. one thousand nine hundred and twenty-eight.

RALPH POLK.
